INVENTOR

Joseph Pedery

BY
F. Ledermann
ATTORNEY

UNITED STATES PATENT OFFICE.

JOSEPH PEDERY, OF NEW YORK, N. Y.

TIE AND COAT-SLEEVE PRESS.

Application filed September 23, 1921. Serial No. 502,603.

To all whom it may concern:

Be it known that I, JOSEPH PEDERY, a citizen of the United States, residing at New York, in the county of New York and State 5 of New York, have invented certain new and useful Improvements in Tie and Coat-Sleeve Presses, of which the following is a specification.

The invention relates to sleeve and tie 10 presses and has for its principal object the provision of a device which is readily inserted in the inner portion of the tie, simple in operation and can be adjusted to suit various widths of ties.

Another object is to provide a device 15 which can be interchangeably used for either neck-tie or for the cold pressing of coat sleeves or trousers of an article of apparel, by reason of the resilient frame members readily 20 adapting themselves to the curvature of the sleeve. Obvious modifications in structure or form and various kinds of materials, may be availed of in the manufacture of my invention without departing from the spirit 25 thereof within the scope of the appended claim.

These and other objects will become apparent in the description to follow in which characters of reference will refer to the like- 30 named parts in the drawing.

Referring more in detail to the drawing, Fig. 1, represents a front elevational view of the device.

Fig. 2, is a side elevational section taken 35 on the line 2—2 of Fig. 1.

Fig. 3, is a section taken on the line 3—3 of Fig. 1.

Fig. 4, is a similar view but shows the device as applied to a sleeve.

Fig. 5, is a front elevational view shown in 40 the device as applied to a neck-tie.

Referring more in detail to the drawing the numeral 10 represents resilient longitudinal side frames, semi-circular bends 11 45 formed at opposite ends of frames 10 have connecting members 12 formed therewith. Extensions 13 and 13' at the extreme ends of the members 12 are slightly bent so as to lie in a plane parallel to frames 10. The entire frame is preferably formed of one piece,

A flat plate member 14 having a projecting member 15 at its lower end is fixedly secured to members 13' by having ears 15', integral with projection 15, form a sleeve around the extensions 13'. The upper end 55 of the plate 14 has a similar projection 16 and has a pin 17 adapted to engage the holes 18 located in the substantially rectangular guide plate 19.

The guide plate 19 is preferably fixed to 60 the extensions 13 by means of ears 20 forming a sleeve for the said extensions 13.

In use the pin 17 fixed to plate 14 can be disengaged from any of the holes 18 and lie free thus permitting free entry into the tie 65 or sleeve. As the frames are composed of resilient material it becomes apparent that the ends 17 will yieldably accommodate themselves to the various widths of ties or sleeves.

Fig. 4, shows the device applied to a coat sleeve 21, with the pin 17 in one of the holes 18 of the guide plate 19. The importance of having the frames yieldably resilient is aptly illustrated in this view by 75 reason of it following the contour of the elbow of the sleeve, the latter being invariably fashioned in this manner.

From Fig. 5, it likewise becomes apparent, 80 that a neck-tie 22 of the four-in-hand variety and having straight tapering lines can also be accommodated in the same manner.

I claim:

A device of the class described comprising 85 resilient frames oppositely disposed to each other and having extensions at the extreme ends thereof, a plate member having a projection at its lower end, sleeves on opposite sides of said projection adapted to fixedly receive the extensions located at the lower end 90 of said frame member, a similar projection at the upper end of the plate, a pin fixed in the said projection, a guide plate having a plurality of holes attached to the opposite ends of the frame members, said pin adapted 95 to engage any of the holes in said guide member.

In witness whereof I affix my signature.

JOSEPH PEDERY,
